(57) **CLAIM**

The ornamental design for a rear spoiler for motor vehicle, as shown and described.

DESCRIPTION

FIG. 1 is a perspective view of a rear spoiler for motor vehicle showing my new design;

FIG. 2 is a rear view thereof;

FIG. 3 is a front view thereof;

FIG. 4 is a right side view thereof, the left side being a mirror image thereof; and,

FIG. 5 is a top view thereof.

The portions of the rear spoiler for motor vehicle shown in broken lines form no part of the claimed design.
